UNITED STATES PATENT OFFICE

2,588,142

PACKAGE DELIVERY CHUTE

Peter T. McQueen, Milnathort, Scotland, assignor
of one-third to William Watson Bowie and one-
third to Herbert Gibson, Edinburgh, Scotland

Application February 20, 1948, Serial No. 9,815

In Great Britain July 9, 1946

Section 1, Public Law 690, August 8, 1946

Patent expires July 9, 1966

8 Claims. (Cl. 193—32)

1

This invention relates to chute for delivering packages from higher to a lower level, and to means for retarding the descent of the packages. The invention is particularly applicable to the delivery of heavy or bulky packages, including sacks, bags and the like, through a vertical or steeply inclined chute, from an upper storey of a building to a lower storey or to ground level.

The invention consists in the provision of means for controlling the descent of the packages comprising a retarding wall movably suspended from a fixed support in an inwardly and downwardly inclined direction within the chute; a cushioning wall movably suspended from said retarding wall, and resilient means normally holding said walls in a position in which they will engage a descending package, said resilient means controlling yielding movement of said walls under the pressure of the package thereon.

The retarding wall is preferably hinged at its upper edge to one wall of the chute, means being provided for supporting the retarding wall in an inclined position in which it partly obstructs the passage of the package through the chute and the said supporting means is arranged to permit the retarding wall to yield on impact of the package thereon. Resilient means are provided for controlling yielding movement of the said retarding wall so that such movement occurs gradually and progressively until the package passes the lower edge of the retarding wall.

The cushioning wall is preferably pivotally suspended in a vertical or substantially vertical position from the lower edge of the retarding wall and is preferably also provided with its own resilient means for holding it substantially in such position while permitting the cushioning wall to yield under the pressure of the package thereon as the package descends the chute. The speed of descent of the package is thus controlled.

In carrying out the invention, the lower edge of the retarding wall may be controlled by means of pulley tackle comprising ropes or cables attached at one end to the lower part of the retarding wall and passing over pulleys on the chute to a counterweight or weighted cross bar, movement of which is controlled by a cataract, dashpot or other hydraulic or fluid-friction buffer device for controlling movement of the ropes or cables. Projections at the ends of the lower edge of the retarding wall may engage in arcuate slots or guides in or on the side walls of the chute.

The cushioning wall may be hingedly suspended from the lower edge of the retarding wall and the lower end of the cushioning wall may be

guided by projections thereon engaging in suitable slots or guides in or on the side walls of the chute. The lower end of the cushioning wall is controlled, in like manner to the upper wall, by means of counterweighted pulley tackle mechanism controlled by a cataract, dashpot or other buffer device.

The packages descending the chute may be delivered on to a fixed or adjustable inclined platform arranged to discharge the packages through an opening in the side of the chute.

If required, there may be two or more similar resiliently controlled cushioning walls pendulously suspended from one another, according to the length of the chute.

The apparatus according to my invention may be fitted in the chute between any two adjacent floors of the building, and such apparatus may be fitted to the chute above each floor, in which case adjustable or movable shutters provided in the chute at floor level can be adapted to be swung open to permit the packages to be delivered to any desired lower level.

The invention may also be applied to a portable chute adapted to be positioned beneath an opening or trap door in the floor of the building.

For boxes, cases or like packages of wood or metal, the retarding wall and cushioning wall or walls may be fitted with fixed metal runners or guides to withstand wear and to guide the package in its descent.

In order that the delivery of packages at the receiving end may be controlled, remote control or emergency stop mechanism operable from the receiving end of the chute may be provided for releasably locking the retarding wall and/or cushioning wall or walls against yielding movement, so as to prevent the descent of the packages.

The invention will be more readily understood by reference to the accompanying drawings which illustrate one example of a chute according to the invention in sectional side view in Fig. 1 and in rear view in Fig. 2, the outer wall being removed in Fig. 2 to show the mechanism.

The chute illustrated has front and rear outer vertical walls 1 and 2 and outer side walls 3. Spaced from the rear wall 2 is an inner vertical wall 4 which forms the rear wall of the passage through the chute. Pivotally suspended from a pivot 5 at the upper end of the front of the chute is a retarding wall or flap 6 normally held in the inclined position shown in full lines in Fig. 1 by the attachment of the lower edge of the flap 6 to cords or cables 7 which pass rearwards

3

over pulleys 8 to a counterweight 9 slidably guided by means of fixed vertical guides 10 in the space between the inner rear wall 4 and the outer rear wall 3. The flap 6 swings between inner side walls 11 which are spaced from the outer side walls 3. The cables 7 are attached to the ends of a hinge pin 12 which is carried by the lower edge of the flap 6 and projects at its ends beyond the side edges of the flap 6 and through arcuate slots 13 formed concentric with the hinge pin 5 in the inner side walls 11. The cables 7 pass from the pulleys 8 to the hinge pin 12 on the outside of the side walls 11, which form the side walls of the passage-way through the chute.

When a package is dropped into the mouth 15 A of the chute, it presses on the flap 6, which yields and raises the weight 9 by its connection thereto. Rising movement of the weight 9 is controlled by the attachment of the weight to a piston rod 14, the piston of which moves in a cylinder 15, connected by a pipe 16 to a tank 17 for oil or other liquid. A valve 18 controls the outlet from the cylinder 15 to the tank 17, and a control member 19 fitted to the valve 18 behind the rear wall 2 enables the rate of flow of liquid from the cylinder 15 to be controlled, thus controlling the rate of upward movement of the weight 9 and consequently controlling the speed at which the flap 6 can yield. The cylinder 15 is shown suspended from a cross rod 20, but it may be mounted in any other convenient manner.

Suspended from the hinge pin 12 and free to hang between the inner side walls 11 of the chute is a cushioning wall 21 which may be of any desired length, its lower edge carrying a hinge pin 22, the ends of which work in openings 23 in the inner side walls 11. The hinge pin 22 is controlled in a similar manner to the hinge pin 12 by connecting it to cables 27 passing over pulleys 28 to a weight 29 guided by guides 10a and attached to the piston rod 14a of a cylinder 15a which has its outlet connected to the pipe 16 through a valve 18a controlled by means of a control member 19a. It will be apparent that movement of the lower end of the movable wall 21 away from the fixed inner rear wall 4 is thus controlled by the rate at which fluid can escape from the cylinder 15a.

As shown in broken lines in Fig. 1, when the flap 6 yields to the position shown at 6a, the movable wall 21 will initially occupy the inclined position shown at 21a until the controlled descent of the package down the chute presses the movable wall into the vertical position shown at 21b, when the package will be released, and falls on to a discharging platform 24 which deflects the package through an opening 25 in the front of the chute. The discharging platform 24 may be fixed or adjustable. On the drawings the lower end of the platform 24 is shown supported on a cross rod 26 cranked at its ends at 26a, the cranked ends being rotatably received in slots provided in slotted plates 32 fixed to the side walls 11. Two or more slots are provided in each plate 32 so that the cross rod 26 can be raised or lowered to raise or lower the discharge platform 24. A lever 33 swivelled on a downturned end of one of the cranked portions of the rod 26 enables the cross rod to be rotated through any desired angle, thus raising or lowering the lower end of the platform 24, and moving it backwards or forwards about the axis of the cranked ends 26a in the slotted plates 32 as centre. The lever 33 has one or more holes 34.

which can be engaged with pins 35 on the side wall 3 to lock the platform 24 in position after adjustment.

The lower end of the movable wall 21 may have a flap or extension 30 pivotally suspended therefrom and connected at its lower edge to the lower edge of the front wall 1 of the chute by a flexible curtain 31 to permit the flap 30 to yield freely for the passage of the package.

If desired the flap 30 may be yieldingly controlled in like manner to the flap 6 and wall 21.

The chute may be either vertical or steeply inclined and may be duplicated, one chute discharging into a lower chute disposed either directly under the upper chute or in staggered relation thereto, and movable or adjustable shutters may be provided between upper and lower chute for discharging the packages at a point intermediate the chute when desired.

By regulating the valves 18 and 18a, the speed at which the fluid is ejected from the cylinders 15 and 15a may be adjusted to control the rate of yielding movement of the flap 6 and wall 21, and thus control the speed of descent of the package through the chute, and by closing either of the valves 18 and 18a, the descent of the package may be arrested.

I claim:

1. In a package delivery chute, a retarding wall movably suspended from a fixed support in an inwardly and downwardly inclined direction within the chute, a cushioning wall movably suspended at its upper end from said retarding wall, and resilient means normally holding said walls in a position to engage a descending package within the chute and controlling yielding movement of said walls to control the rate of descent of the descending package under the pressure of the package thereon.

2. In a package delivery chute, a retarding wall hinged at its upper edge to a fixed support, means yieldingly maintaining said wall in a position in which it partly obstructs the chute, a cushioning wall pivotally suspended at its upper end from the lower edge of said retarding wall, and cushioning means normally maintaining said cushioning wall in yieldingly suspended position.

3. In a package delivery chute, a retarding wall movably suspended from a fixed support in an inwardly and downwardly inclined position within the upper part of the chute, cushioning means permitting controlled yielding movement of said wall to permit controlled passage of a descending package past said wall, means for regulating said cushioning means to vary the rate of yielding movement of said wall, a cushioning wall freely suspended at its upper end from the lower edge of said retarding wall, and adjustable cushioning means acting on said cushioning wall to permit controlled yielding movement thereof in contact with the descending package.

4. A package delivery chute having rigid walls defining three sides of the chute, a retarding wall movably suspended at its upper end in said chute, means urging said retarding wall inwardly into an inwardly and downwardly inclined position, means limiting inward movement of said retarding wall, a cushioning wall suspended at its upper end from said retarding wall, means urging the lower end of said cushioning wall inwards, and means limiting inward movement of said cushioning wall.

5. A package delivery chute having rigid walls defining three sides of the chute, a movably suspended flap defining the fourth side of the upper

4

part of said chute, resilient mechanism acting on said flap to yieldingly urge the lower end of said flap inwards, means limiting inward movement of said flap, a cushioning wall suspended from said flap, resilient mechanism acting on said cushioning wall to yieldingly urge it to move inwards, and means limiting inward movement of said cushioning wall.

6. A package delivery chute having rigid walls defining three sides thereof, a hingedly suspended flap defining the fourth side of the upper part of said chute, a cushioning wall pendulously supported from said flap and defining the fourth side of said chute below said flap, mechanism connected to and urging the lower end of said flap and the upper end of said cushioning wall inwards, means limiting such inward movement, means acting to move the lower end of said cushioning wall inwards, and means limiting inward movement of the lower end of said cushioning wall.

7. A package delivery chute comprising rigid walls defining three sides thereof, a flap defining the fourth side of the upper part of said chute, hinge means for the upper end of said flap, a cushioning wall defining the fourth side of said chute below said flap, a hinge connecting the lower end of said flap to the upper end of said

5 cushioning wall, means permitting limited travel of said hinge in an arcuate path concentric with the axis of the hinge means for the upper end of said flap, means resiliently acting on said hinge to move the lower end of said flap and said cushioning wall inwards into the chute, and means resiliently controlling the position of the lower end of said cushioning wall.

8. A chute as specified in claim 7 in which the hinge is connected to resilient controlling means.
